UNITED STATES PATENT OFFICE

160,633

COLLAPSIBLE HIGH CHAIR

Alfred T. Kvarnstrom, Walled Lake, Mich.

Application June 28, 1948, Serial No. 147,242

Term of patent 7 years

(Cl. D15—8)

To all whom it may concern:

Be it known that I, Alfred T. Kvarnstrom, a citizen of the United States, residing at Walled Lake, in the county of Oakland and State of Michigan, have invented a new, original, and ornamental Design for Collapsible High Chair, of which the following is a specification, reference being had to the accompanying drawing, forming part thereof.

In the drawing

Fig. 1 is a perspective view of a collapsible high chair, showing my new design;

Figure 2 is a side view of the same; and

Figure 3 is a plan of the same.

I claim:

The ornamental design for a collapsible high chair, as shown.

ALFRED T. KVARNSTROM.
